Sec. 80

Calvin Fullon (assignor to John M. French) Rochester, N. Y.
Letters Patent (Design No. 80) dated 18th August 1846

The Schedule referred to in these Letters Patent and making part of the same.

To all whom it may concern:

Be it known, that I, Calvin Fullon of the City of Rochester, County of Monroe and State of New York, have invented or produced, a new ornamental design for a cooking stove, and I do hereby declare that the following is a full and exact description of the same, reference being had to the annexed drawings making a part of this Specification, in which Fig. 1 is a perspective view, Fig. 2 elevation showing the ornaments enlarged, Fig. 3 shows a section through dotted line A. B. Fig. 4 shows a part of the oven door C. Fig. 1. Fig. 5 shows a section through dotted line D. E. Fig. 4. Fig. 2 shows the moulding G. to Fig. 1 enlarged H. Fig. 2 shows the door I fig. 1 enlarged, J fig. 2 shows the mouldings K. H. Fig. 1 enlarged.

What I claim as my invention and desire to secure by Letters Patent is the design and combination of ornamental cooking stove, as herein described.

Witnesses,

End P. C. Bushan
J. R. E. Bottenus
